UNITED STATES PATENT OFFICE

WILL R. JOHNSON, OF STOCKTON, CALIFORNIA, ASSIGNOR TO RICHMOND-CHASE COMPANY, OF SAN JOSE, CALIFORNIA, A CORPORATION

DISTRIBUTOR FOR GRADING MACHINES

Application filed June 7, 1930. Serial No. 459,696.

This invention relates to grading machines by means of which products of various kinds are graded and segregated according to size, and particularly relates to a means for initially delivering such produce onto the grader from a source of supply or from an inspection table or other mechanism used in a preceding operation.

The principal object of my invention is to provide a distributor for the purpose so arranged that matter delivered thereon at one end from a relatively narrow conveyor or chute, will be automatically spread out and discharged with practically equal volume into the grading slots of a grader of considerably greater width than said conveyor or chute. By means of this arrangement a grading machine having a relatively great number of transversely spaced grading troughs or openings may be used, so that a large volume of matter may be graded at one operation, and without the objectionable feature of having certain ones of the grading troughs over-full and others starved, in which case the grader would not work to best advantage, as will be evident.

I have particularly in mind to use this distributor in connection with the grading of asparagus and in connection with the grader shown in my co-pending application for patent, Serial No. 458,069 filed May 31, 1930. It will be evident however from the accompanying description that its use is not limited to this purpose nor to association with the particular grading machine.

A further object of the invention is to produce a simple and inexpensive device, and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a top plan view of the distributor.

Fig. 2 is a longitudinal section of the same.

Fig. 3 is an end view of the distributor at

its discharge end, and taken as if the distributor were disposed in a horizontal plane.

Referring now more particularly to the characters of reference on the drawings, the grader herein shown and to which the distributor is attached, is of that type shown in said copending application for patent, and includes a frame 1 set on a downward slope and mounted for longitudinal shaking movement on rails 2 which form the main support for the entire structure.

Mounted in the frame 1 are a plurality of longitudinally extending pairs of rollers 3, the space between the rollers of each pair forming the grading slots 4. The upper surfaces of the adjacent rollers of adjacent pairs are covered by inverted V-shaped members 5, which with the corresponding rollers, form substantially V-shaped troughs 6, the bottoms of which are the slots 4.

My improved distributor which is mounted in connection with this grader comprises a supporting frame which consists essentially of side bars 7 secured to and projecting forwardly from the sides of the frame 1 at the upper end of the grader, so as to move or shake with said grader and being disposed at the same slope as the grader. At its forward end this frame is preferably supported by a roller 8 riding on a plate 9 which is mounted on bars 10, which in turn project from and are supported by the rails 2. Side plates 11 are secured to and extend along the bars from end to end of the same, and said bars converge toward each other from the frame 1, so that the side plates are also disposed in converging relation.

At the lower wide end of the distributor frame is a distributor platform 12 extending between the plates 11 in overhanging and clearance relation to the adjacent ends of the grader members 5. This platform is bent to form a plurality of transverse longitudinally extending ridges and troughs 13 arranged in alternate relation; the troughs being disposed in transverse and substantially longitudinal alignment with the grader troughs 6, while the peaks of the ridges are transversely

alined with the peaks of the members 5, as shown in Fig. 3.

Ahead of the platform 12 and overhanging the adjacent end of the same somewhat is another platform 14, disposed on a somewhat higher level than said platform 12 and also extending the full distance between the side plates 11. This platform is also bent to form a number of transverse longitudinally extending ridges and troughs 15 arranged in alternating relation; the bottom of these troughs transversely alining with the peaks of the ridges of the platform 12, and the peaks of said platform 14 transversely alining with the bottoms of the troughs 13.

Ahead of the platform 14 and overhanging the adjacent end of the same somewhat is still another platform 16, disposed on a somewhat higher level than said platform and extending between the side plates 11. This platform is likewise bent in the form of a number of transverse longitudinally extending ridges and troughs 17 arranged in alternating relation to each other; the bottoms of these troughs transversely alining with the peaks of the ridges of the platform 14 and the peaks of said platform 16 transversely alining with the bottoms of the troughs 15 of the platform 14. Upstanding pins 18 project from the peaks of the ridges of all the platforms adjacent their rear ends.

Forwardly of the platform 16 and on a higher level is another platform 19 which overhangs the adjacent end of the platform 16 and extends to the front end of the plates 11. At its forward end this platform is flat but toward and to its rear end it gradually assumes a transverse convex curvature, as shown at 20.

Projecting upwardly from the convexly curved portion of this platform near its rear end is a centrally disposed deflector 21. The matter to be graded is disposed onto the forward end of the platform 19 by means of a conveyor 22 or any other suitable device. It will thus be seen that the supporting surfaces of the distributor are arranged as a series of steps of gradually increasing width from front to rear. The matter to be graded, discharged onto the platform 19 as stated, travels down said platform partly by gravity on account of the slope at which the distributor is set and partly by the shaking action. When the matter reaches the curved portion of said platform it is naturally deflected toward the sides both on account of said curvature and by reason of the deflector 21. The curvature is such that all the troughs 17, which the platform 19 overhangs, receive substantially equal amounts of the matter dropping off said platform. The matter then moves down the troughs 17 which

overhang and are centrally disposed between adjacent troughs 15 of the discharge step 14 below. This relative positioning of the troughs of the two platforms causes the matter to be discharged with substantially equal volume into all the troughs 15 of such lower step. From the troughs 15 the matter is delivered in turn equally to all the troughs 13 of the lowest step 12 on account of the relative setting of the troughs 15 and 13. The troughs 13 being actually alined with the grader troughs all the troughs of the latter receive equal quantities of the matter to be cleared.

Since the number of steps and the number of troughs and ridges in each step, may be increased almost indefinitely without increasing the width of the distributor at its feed-in or receiving end, it will be seen that a very wide grader may be effectively used, with the assurance that all the grader troughs will receive substantially equal quantities of the matter being graded.

From the foregoing description it will be readily seen that I have produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A material distributor for graders comprising a series of distributor elements arranged in steps rising in a direction longitudinally of the grader, each step being corrugated and each step being longer than the preceding step, the ridges and grooves of the corrugations of one step being in a different transverse plane than those of adjacent steps.

2. A material distributor for graders comprising a series of distributor elements arranged in steps rising in a direction longitudinally of the grader, each step being corrugated and each step being longer than the preceding step, the ridges of the corrugations of one step being in substantial longitudinal alinement with the grooves of adjacent steps.

3. A material distributor for graders comprising a series of distributor elements arranged in steps rising in a direction longitudinally of the grader, each step being corrugated and each step being longer than its preceding step and upstanding pins at the rear ends of the ridges of corrugations of each step.

WILL R. JOHNSON.
